DOOR LATCH

Boyd N. Carlson, El Monte, Calif.

Application January 13, 1959, Serial No. 138,313

11 Claims. (Cl. 20—16)

1

The present invention relates to door latches in general and particularly to a latch for overhead doors. More specifically the invention comprises a latch for overhead doors which automatically retains the door in an open position and which is releasable upon the pulling of a release cord hanging downwardly through the door.

The overhead door is widely used, particularly in garages. Its characteristics are such that a door of relatively great height, length and weight can be opened in a single operation, the presence of counterbalancing springs materially reducing the force required from the operator. Usually such doors in their closed position extend vertically and are substantially in alignment with, or at least parallel to, the front wall of the garage or building of which they are a part. In their raised or open position they extend horizontally, or substantially so, and are at a sufficient height that persons and/or vehicles, such as automobiles, can pass thereunder.

It has been the experience of users that while overhead doors are opened with surprisingly little effort, and this is because of the presence of the counterbalancing springs, yet the effective counterbalancing of the forces and weights frequently produces a balance so sensitive that the door is sometimes displaced accidentally from its raised open position by vibration or by the force of wind. Stated differently, the establishment of a sensitive balance between the counterbalancing spring and the weight of the unit too frequently results in a condition of unstable equilibrium with the door raised. While this could be overcome in certain instances by increasing the strength of the counterbalancing spring, or by placing additional weights on the door at proper positions, such a step would adversely affect the relationship making the door easy to handle.

With an appreciation of the usefulness and operating characteristics of overhead doors it is a primary purpose of the present invention to provide a latch for overhead doors which automatically retains them in their raised open position against accidental displacement.

A further object of the present invention is to provide a latch for overhead doors which comprises elements upon the door and upon the building which cooperate to effect a positive locking action to retain the door in its raised open position, and which is releasable by the user upon pulling a release member extended downwardly through the door.

2

Still another object of the invention is to provide a latch for overhead doors which functions not only to prevent a door from pivoting downwardly, but which also is adapted to support a part of the weight of the door in the raised open position.

These and other more specific objects will appear upon reading the following specification and claims and upon considering in connection therewith the attached drawing to which they relate.

Referring now to the drawing in which a preferred embodiment of the invention is illustrated:

15 Figure 1 is a vertical section through a building incorporating a pivoted overhead door retained in its raised open position by means of a latch constructed in accordance with the present invention;

20 Figure 2 is an enlarged showing of the door-retaining latch illustrated in Figure 1 in its locking relationship;

Figure 3 is a view looking in the direction of the arrows upon the line 3—3 of Figure 2; and

25 Figure 4 is a showing similar to Figure 2 but with the latch pivoted to release the door under an operator-provided force.

In the drawing, and in Figure 1 in particular, an overhead door is illustrated pivotally mounted in a doorway in the wall of a building. The latter is indicated generally by the reference character 10, the door generally by the reference character 11, and the latch unit, comprising the present invention, is indicated generally by the reference character 12.

35 The building may be of any type and made of any conventional material, it being important only that it be provided in one wall with a doorway such as is indicated generally by the reference character 13. The doorway shown in Figure 1 includes side members 14, of which one is illustrated, and a transverse top member 16. The front wall of the building is indicated generally by the reference character 17, and its roof by the reference character 18.

Door 11 may be of conventional size and shape, for example, about 12 to 15 feet long and about 7 feet high. It may be of wood or metal and should have sufficient rigidity as to maintain itself in a single plane in both the vertical and in the horizontal positions. In the illustrated form the door includes side frame members 21 connected by cross-members 22 over which lie the face or wall 23.

55 Each end or side of the door is pivotally sup-

ported for movement between a vertical position, in which it is even with the front of the doorway 13 and closes that aperture, and an upper, raised or open position, as illustrated in Figure 1. The pivotal mounting at each end comprises a pair of spaced arms 26 and 27 fixedly connected at one end to a member 28 affixed to the door frame member 21. At their opposite ends arms 26 and 27 are pivoted on a bracket 29 secured fixedly to the side member 14 of the doorway.

The arm 26 at each end of the door is extended beyond its pivot on bracket 29 and is provided with a plurality of openings 31 adapted to receive and seat one end of an elongated coil spring 32 the opposite end of which is suitably secured, as by a bracket 33, to the doorway side member 14. Spring 32 at all times exerts a pivotal force upon the arm, tending to raise door 11 from its vertical to its horizontal position. With the door in the latter position the spring exerts a force on its connected arm 26 to retain the door against accidental downward displacement. The presence of a plurality of spaced holes 31 along the arm 26, each adapted to seat the end of the connected spring 32, makes it possible to vary the spring force and its effective lever arm about the pivot point of arm 26. It is possible to so tension the springs 32 that the force required to lift the door is minimized, but the difficulty lies in the fact that when the balance is accurately established the force which the spring exerts in retaining the door in its raised position, as illustrated in Figure 1, is frequently too small and the door may accidentally pivot from its open to its closed position.

The latch unit 12 constructed in accordance with the present invention comprises a base plate 36 secured by screws 37 to the building wall 11. Integral parallel plates 38 extend outwardly from base plate 36, each being formed with a lower edge 39 which slopes downwardly and outwardly. One plate 38 is formed with a transverse lip 41 which extends across to the adjacent plate to provide a stop, as will be described. Between the plates 38 the latch 46 is pivoted upon a pin 47 extended therebetween. Latch 46 extends above and below pin 47, being formed adjacent the curved surfaces 39 with a shoulder 48 below which extends its own curved surface 49 conforming generally to the curvatures 39 of plates 38 although somewhat longer. Above its pivot 47 latch 46 extends upwardly to a point opposite the stop 41 which it is adapted to contact in a limiting angular position. On its side spaced from the stop it is formed with an outwardly projecting nipple 51 which seats one end of a coil spring 52 the opposite end of which seats upon a pin 53 carried by base plate 36. Coil spring 52 at all times urges lever or latch 46 in a clockwise direction, as viewed in Figures 2 and 4, to cause its upper end to abut the stop 41. When so positioned shoulder 48 projects beyond the curved edges 39 of the plates 38. A second coil spring 54 encircles the pivot pin 47 and, through engaging one of the plates 38 at one of its ends and the latch 46 at the other, exerts a pivoting force supplemental to that of spring 52.

The latch unit base plate 36 is secured to the wall 11 of the building directly above, and preferably centrally of, the doorway so that the latch 46 extends vertically with its pivot pin 47 and its shoulder 48 horizontal as illustrated in the drawing.

Carried by the front face of the door 11 and

positioned thereon as to move into cooperative relationship with the latch 46 is a hook 56 formed at the outer end of an offset arm 57 of a plate 58 secured by screws 59 to the face 23 of the door. The offset arm 57 is so located on door 11 that with the door in its raised position the arm is positioned immediately forward of the building front wall 17, and its length is such that when so positioned the end of the hook 56 overlies shoulder 48 of latch plate 46. Pivotedly mounted upon the hook plate 58 is a release plate 61 which is V-shaped with its apex rockingly connected for pivotal movement by a pin or pins 62 at the angle between the arm 57 and plate 58. The end of the release lever or plate 61 extends just short of the end of hook 56 and in position to contact the curvature 49 of the plate 46 immediately adjacent the shoulder 48 with the hook and latch engaged. This relationship is most clearly shown in Figure 2. The force exerted by springs 52 and 54 acting through the latch 46 holds the release lever 61 in the position illustrated in Figure 2.

The lower end of release plate or lever 61 extends adjacent the plate 58, and with the lever in its normal engaged position, as illustrated in Figure 2, it is spaced therefrom angularly as shown in Figure 2. An eye bolt 63 extends upwardly through an aperture 64 in the door face 23, and aligned apertures 66 and 67 in the plate 58 and lever 61, respectively. A nut 68 seated upon the threaded upper end of eye bolt 63 rests upon latch plate 61 while a cord 69 is attached to its lower end and hangs below the door, as illustrated in Figure 1. The cord should have a sufficient length that a person standing upon the floor can reach upwardly and grasp it. The weight of eye bolt 63 and connected cord 69 acting through the lever plate 61 is not sufficient to pivot the latter to displace the latch 46 from hook 56 against the force exerted by coil springs 52 and 54.

The operation of the latch mechanism constructed in accordance with the present invention when incorporated in an overhead door is as follows. Let it be assumed that the door 11 is first in a vertical position in which it closes doorway 13 and its face 23 is parallel to the face 17 of the building. If it is desired to open the door an upward force is exerted upon the outwardly extending rigid arm 57 of hook plate 58 which, with the door in a vertical position, functions as a handle and extends horizontally and at a convenient height to receive the lifting force. The lifting force, supplemented by the counterbalancing effect of the coil springs 32 at its opposite ends, causes the door to swing upwardly, the arms 26 and 27 pivoting about their pivotal connections on their brackets 29. As the door moves into its raised horizontal position, as illustrated in Figure 1, the curved rounded end of hook 56 contacts the downwardly and outwardly projecting curved surface 49 of pivoted latch 46. The movement of the hook is primarily vertical at this arc of the door's travel and as it moves upwardly it cams the curved edge 49 of the latch to the right, as viewed in the drawing, so that that edge approaches parallelism with the curved edges 39 of side plates 38. The hook 56 continues its upward travel until its hooked end passes latch shoulder 48 whereupon the latch is immediately pivoted under the urging of coil springs 52 and 54. The shoulder 48 moves under the downwardly extending end of hook 56, at the same time forcing release plate 61 to the position

in which its lower portion is spaced from the plate 58, as shown in Figure 2. In the latter relationship, it is to be noted, the door cannot pivot downwardly for the lower end of the hook engages the latch shoulder 48. The downward force thus exerted is apposed by the latch which is carried by its pivot pin 47 almost immediately thereabove.

Let it be assumed that it is desired to lower the door. A downward force on the door itself would not produce the desired result because of the engagement of the hook 56 with the latch shoulder 48. To effect the release of the door a downward force is exerted upon the cord or rope 69. That force is transmitted through the bolt 63 and nut 68 to release lever or plate 61 to pivot it in a clockwise direction until it abuts hook plate 58, a position illustrated in Figure 4. The upper end of release plate 61 in this movement forces the latch 46 in a counterclockwise direction from the position illustrated in Figure 2 to that illustrated in Figure 4 in which the shoulder 48 no longer underlies the hook 56. A continued downward force upon the cord 69 pulls the end of the hook past the latch shoulder 48 whereupon the door is free to continue its downward pivotal movement. The operation can, of course, be repeated.

The latch of the present invention functions not only to retain the overhead door against accidental downward displacement but also functions to prevent sagging. Such doors being relatively long tend to sag in the middle in their raised position and this frequently results in permanent warping. The latch of the present invention prevents the pivotal movement of the door and additionally, through the cooperation of the pivoted latch 46 and the hook 56 in their engaged relationship, prevents downward sag. The hook 56 engages the latch shoulder 48 almost directly under the pivotal axis 47 of the latch so that the downward weight of the door provides no pivotal movement in the latch and instead the latch functions as a support.

While the particular apparatus herein shown and described in detail is fully capable of attaining the objects and providing the advantages hereinbefore stated, it is to be understood that it is merely illustrative of the presently preferred embodiments of the invention and that no limitations are intended to the details of construction or design herein shown other than as defined in the appended claims.

I claim:

1. In an overhead swinging door construction, a frame forming a doorway, a door formed with an aperture and pivotally mounted in said doorway for pivotal movement between vertical closed and horizontal raised positions, a pivoted latch mounted on said frame above said doorway, a hook fixed to the forward face of said door at a position to move into overlying engagement with and to be supported by said latch with said door in its raised position, and release means carried by said door to pivot said latch to release said hook and including a cord hanging downwardly through the aperture in said door with said door in its raised position.

2. In an overhead swinging door construction, a frame forming a doorway, a door pivotally mounted in said doorway for pivotal movement between vertical closed and horizontal raised positions, a spring-pressed pivoted latch mounted on said frame immediately above said doorway, a hook fixed to the forward face of said door in

a position to move substantially vertically into engaging position with said latch during the final part of the movement of said door into its raised horizontal position, said hook being supported by said latch to support said door with the latter in its raised position, a release lever carried by said door to pivot said latch from its engagement with said hook, and a release element connected to said release lever and extended downwardly through said door and through which an actuating force can be exerted on said release lever.

3. In an overhead swinging door construction, a frame forming a doorway, a door pivotally mounted in said doorway for pivotal movement between vertical closed and horizontal raised positions, a spring-pressed pivoted latch including a normally horizontal shoulder and a curved approach surface adjacent thereto, a hook fixed to the forward face of said door in a position to move substantially vertically into contact with the curved approach surface of said latch to cam the latter aside as said hook moves above said latch shoulder, said latch pivoting under its spring pressure to position said shoulder under said hook to support it and the attached door, a release lever carried by said door and positioned as to be adjacent said latch with said hook overlying said latch shoulder, and a release element to actuate said release lever to pivot said latch and displace its shoulder from under said hook to permit said door to swing downwardly.

4. In an overhead swinging door construction, a frame forming a doorway, a door pivotally mounted in said doorway for pivotal movement between vertical closed and horizontal raised positions, a spring-pressed pivoted latch including a normally horizontal shoulder and a curved approach surface adjacent thereto, a hook fixed to the forward face of said door in a position to move substantially vertically into contact with the curved approach surface of said latch to cam the latter aside as said hook moves above said latch shoulder, said latch pivoting under its spring pressure to position said shoulder under said hook to support it and said door attached to it, a release lever carried by said door and positioned as to be adjacent said latch with said hook overlying said latch shoulder, and means to actuate said release lever to pivot said latch and displace its shoulder from under said hook to permit said door to swing downwardly, said means comprising an extension of said release lever extended adjacent the face of said door and normally held spaced therefrom by said lever in contact with said latch while in its latching position, and an element connected to said release lever and extended downwardly through said door while in a horizontal position and through which a lever-actuating force can be transmitted.

5. The construction recited in claim 4 characterized in that said hook is rigidly mounted on the forward face of said door and provides means by which a lifting force may be transmitted to said door.

6. In an overhead swinging door construction, a frame forming a doorway, a door pivotally mounted in said doorway for pivotal movement between vertical closed and horizontal raised positions, a latch unit to retain and support said door in said horizontal raised position and including cooperating parts on said frame and on said door, the parts on said frame comprising a bracket positioned immediately above said doorway and including a base plate and parallel

outwardly extending vertical plates, and a spring-pressed latch pivoted between said vertical plates, the part on said door comprising a rigidly mounted hook so constructed and so located on said door as to move into overlying engagement with said latch as said door moves into its horizontal raised position in order to be supported by said latch and in order to support said door, and release means to pivot said latch from its engagement with said hook and including an element connected to said latch and extending downwardly through said door.

7. In an overhead swinging door construction, a frame forming a doorway, a door pivotally mounted in said doorway for pivotal movement between vertical closed and horizontal raised positions, a pivoted latch mounted on said frame immediately above said doorway, a hook fixed to the front face of said door in a position to move substantially vertically into engagement with said latch during the final portion of the movement of said door into its raised horizontal position, said latch being movable into position to overlie said hook to receive a supporting force and to prevent the vertical downward displacement of said hook and the attached door, and a manually operable release unit to release said latch from said hook to permit said door to pivot downwardly.

8. In an overhead swinging door construction, a frame forming a doorway, a door pivotally mounted in said doorway for pivotal movement between vertical closed and horizontal raised positions, a pivoted latch mounted on said frame immediately above said doorway, a hook fixed to the front face of said door in a position to move substantially vertically into engagement with said latch during the final portion of the movement of said door into its raised horizontal position, said latch being movable into position to overlie said hook to receive a door-supporting force and to prevent the vertical downward displacement of said hook and the attached door, a release lever carried by said door to pivot said latch from its overlying relationship to said hook, and a member connected to said release lever extended downwardly through said door adapted to receive a downward force to actuate said release lever and thereafter to pivot said door downwardly.

9. A latching mechanism comprising cooperating latch and hook units, said latch unit including a frame having a supporting base and spaced parallel plates secured to said base on one side thereof and forming an open-sided and open-ended housing, a plate-like latch pivoted between said parallel plates for pivotal movement in a plane parallel thereto, said latch having a horizontal shoulder extended at an angle to a radius

5 centered on the pivotal axis of said latch and also having a curved approach surface adjacent said shoulder, and a spring urging said latch to a normal latching position in which said shoulder extends to and said approach surface is located at one side of said parallel plates, said hook unit including a hook member adapted to be secured to a body to be releasably connected to said latch unit, said hook member including a run adapted to be fixedly connected to said body and a run extended angularly therefrom and formed with a rounded overhanging end adapted to be moved into displacing contact with said curved approach surface to displace said latch between said plates, the end of said hook member being adapted to extend horizontally over and rest upon said shoulder upon said latch being returned to its initial position upon the hook member passing said curved approach surface, said hook unit 10 also including a pivotal latch-displacing lever having two angularly related runs one of which extends along the run of said hook member adapted to be fixedly connected to said body and the other of which extends to a point adjacent the overhanging end of the other run of said hook member, said lever being pivotally connected to said hook member for movement against the curved approach surface of said latch to displace said latch shoulder from under the end of said hook member to enable said latch and hook units to be relatively displaced, and a member to receive a force from an operator to effect the pivotal movement of said lever.

10. The construction recited in claim 9 characterized in that said hook member and said lever are metal plate elements and in that the included angle between the runs of said lever is less than the included angle between the runs of said hook member.

11. The construction recited in claim 10 characterized in that said lever member and said hook member are pivotally connected at the apexes of the included angles of their respective runs.

BOYD N. CARLSON.
